CARBURETOR FLOAT VALVE STABILIZER

Harold A. Carlson, Brentwood, and James T. W. Moseley, Richmond Heights, Mo., assignors, by mesne assignments, to ACF Industries, Incorporated, a corporation of New Jersey

Application June 27, 1955, Serial No. 518,058

9 Claims. (Cl. 137—39)

This invention relates to automotive fuel supply devices of the type incorporating a constant level liquid fuel chamber and consists, particularly, in novel means for preventing abnormal or excessive supply of fuel to the chamber in case of surging in the fuel chamber caused by a change in the speed or direction of travel of the vehicle.

Such surging of the fuel may permit the float to drop and the inlet needle valve to open, so that a spurt of fuel will be admitted to the fuel chamber. This fuel excessively raises the level in the chamber to greatly enrich the fuel supply, or even cause the fuel to spill out into the carburetor or intake manifold. The result may be temporary uneven operation or stalling of the vehicle, and is noticed particularly when the vehicle is suddenly stopped. At such time, the engine should continue idling, utilizing only the relatively small quantity of fuel supplied through the idling system. An excessive supply due to raising of the level in the fuel bowl, as explained above, may seriously affect the operation of the engine.

In the present invention there is provided an additional inlet valve control, namely, an eccentric baffle or weight or other inertia member which responds to surging of the fuel or a change in the speed or direction of travel to urge the inlet valve closed, notwithstanding a momentary dropping of the float which, otherwise, would permit the needle valve to open.

In the accompanying drawing which illustrates the invention,

Fig. 1 is a side view partially cut away and sectioned, illustrating an automotive carburetor embodying the invention.

Fig. 2 is an enlarged detail of the sectioned portion of the structure in Fig. 1, including the fuel inlet valve and its controlling parts.

Fig. 3 is a detail elevation and section taken on line 3—3 of Fig. 2.

The carburetor illustrated is of the downdraft type, including a mixture conduit or barrel 5 and a fuel bowl or chamber 6, within which fuel is maintained at a substantially constant level X—X by means of a float 7 which acts upon a needle valve 8 located in the inlet connection 9 having ports 9a. This connection is threaded in the usual way, at its inlet end, for attachment to a fuel line leading to the fuel supply pump (not shown). In the lower part of the carburetor barrel, there is provided the usual butterfly throttle valve 10, which is operated from the accelerator pedal located in the driver's compartment.

In the lower portion of the constant level chamber 6, there is provided a main metering orifice element 11, controlled by metering pin 12, through which fuel is supplied to main fuel passage 13 discharging into a venturi tube 14 within the mixture barrel. Fuel for idling is supplied through passages 15 connecting the main fuel passage and idle port or ports 16 located adjacent and slightly posterior to the throttle valve when closed.

Float 7 has a supporting arm 19 pivotally mounted by means of a pin 20 to the depending structure 21 on float

2

bowl cover 22. Arm 19 has an upwardly bent finger 23 projecting toward needle valve 8 for closing the same. Also pivotally mounted on pin 20 is an angular element 24 having, at one end, a lip 25 interposed between finger 23 on the float arm and inlet needle valve 8. At the other end of element 24, there is provided an eccentric baffle and weight 26 of substantial area, as shown in Fig. 3.

In operation, float 7 acts through arm 19 and lip 23 to control needle valve 8 for maintaining fuel within the bowl at the substantially constant level X—X. When the float drops for any reason, valve 8 is urged open by its weight and the pressure of fuel in inlet 9. The several ports 9a in the inlet member provide for rapid admission of fuel into the bowl upon opening of the needle valve. During normal operation, eccentric element 24 oscillates slightly with the float to actuate the needle valve, and does not adversely affect the normal constant level mechanism. However, in case of a sudden slackening of the vehicle speed, the element 24 will be thrown forward by inertia action, causing finger 25 to bear against needle valve 8 and tend to hold the same closed. At the same time, the surging fuel, as indicated by line Y—Y in Fig. 2 acts directly on member 26 as a baffle, applying further force tending to close valve 8. Such urging permits the float to drop, as to the broken line positioning of arm 19 in Fig. 2 and, except for the baffle or inertia element, the needle valve would open. Of course, the dropping of the float does not affect this additional control of the needle valve.

The eccentric weight and baffle may be mounted otherwise, and may be arranged to respond to different changes in velocity or direction, in other words, such changes in the condition of motion (or lack of motion) as cause surging in the fuel and resultant change in the fuel level and the level influenced valve control. Moreover, element 26 may be of relatively light, broad construction so that its chief effect is due to the surge of fuel against it rather than its own inertia, or vice versa. It is understood that the weight baffle responds to any such change of movement as would cause surging of the fuel, which would permit the float to drop and the needle valve to open, except for the inertia-baffle control. This application is a continuation in part of a co-pending application, Serial No. 268,812, filed January 29, 1952, now abandoned. The exclusive use of all modifications as come within the scope of the appended claims is contemplated.

Although this invention has been described with particular reference to certain features, embodiments, and functional relationships, various changes will be apparent to one skilled in the art, and the invention is therefore not to be limited to such features, embodiments, or functional relationships except as set forth in the appended claims.

We claim:

1. In a fuel supply device for mobile internal combustion engines, a constant level reservoir having an inlet connection, an inlet valve in said connection, a float operatively connected to said valve to maintain a constant level of fuel in said reservoir, and an additional control for said valve acting independent of fuel level comprising an eccentrically pivoted weight also operatively connected to said valve and displaced substantially from its pivotal support in a vertical direction for urging said valve closed by inertia effect upon sudden change in the condition of motion of the device.

2. In a constant level liquid supply device, a reservoir having an inlet connection, an inlet valve therefor, a float in said reservoir operatively connected to said valve for closing the same when the fuel stands at or above the desired constant level and opening said valve when the fuel drops below said level, and an inertia element acting independent of said float also operatively connected to

said valve and capable of horizontal movement relative to said reservoir, upon sudden change of condition of motion of the reservoir for closing said valve irrespective of the liquid level in said reservoir.

3. In a fuel supply device for the engine of an automotive vehicle, a fuel chamber having an inlet connection, constant level maintaining means comprising a valve for said inlet and a float for closing said valve when supported by the fuel at or above the desired constant level, and a separate valve control consisting of an eccentrically pivoted weight having an operative connection to said valve and displaced substantially vertically of its pivotal support so as to shift horizontally by inertia effect, upon sudden change in the condition of motion of the device, to independently close said valve and compensate for dropping of said float due to surging of the fuel in said chamber.

4. In an engine fuel supply device for a vehicle, a reservoir having an inlet fuel connection, an inlet valve in said connection, a float in said reservoir operatively connected to said valve for actuating the same to maintain a constant level of fuel in said reservoir, and a separate valve control having an operative connection to said valve including a lever pivoted about an axis at right angles to the normal direction of travel of the device, a weight on said lever displaced substantially vertically from said axis whereby said weight is shifted relative to said reservoir, by inertia effect, upon a sudden change in the rate of travel of the device, to close said inlet valve independently and compensate for dropping of said float due to surging in the fuel.

5. In an engine fuel supply device for a vehicle, a reservoir having an inlet fuel connection, an inlet valve in said connection, a float in said reservoir operatively connected to said valve for maintaining fuel in said reservoir at a substantially constant level, said float being connected to said valve by means of a pivoted lever, and a separate inertia control for said valve comprising a bell crank pivoted about an axis at right angles to the normal direction of travel of the device and a weight carried on one arm of said bell crank and displaced substantially vertically from said pivotal axis, the other arm of said bell crank being interposed between said inlet valve and said first mentioned lever whereby shifting of said weight due to change in the rate of travel of the device tends to close said inlet valve independently irrespective of the fuel level in said reservoir.

6. In a fuel supply device for mobile internal combustion engines, a constant level reservoir having an inlet connection, an inlet valve in said connection, a float operatively connected to said valve to maintain a constant level of fuel in said reservoir and positioned in said reservoir to urge said valve in a closing direction in response

to a surge of fuel in said reservoir in one direction, and an additional control for said valve acting independent of fuel level, comprising an eccentrically pivoted weight also operatively connected to said valve and displaced substantially from its pivotal support in a vertical direction for urging said valve closed by inertia effect upon sudden change in condition of motion of the device, producing a surge of fuel in said reservoir in the opposite direction to said first direction.

5 7. In a constant level liquid supply device, a reservoir having an inlet connection, an inlet valve therefor, a float in said reservoir operatively connected to said valve for closing the same when the fuel stands at or above the desired constant level and opening said valve when the fuel drops below said level, and an inertia-baffle element also operatively connected to said valve and capable of movement independently of said float, upon sudden change of condition of motion of the reservoir and surging of fuel therein, for closing said valve irrespective of the liquid level in the reservoir.

10 8. In a constant level liquid supply device, a reservoir having an inlet connection, an inlet valve in said connection, a valve actuating mechanism including a float in said reservoir operable to maintain a substantially constant fuel level, in the reservoir, and another valve actuating mechanism operable responsive to sudden change in condition of motion of the device to close said inlet valve independently of said first-mentioned mechanism, said other valve actuating mechanism including a weight movable relative to the reservoir responsive to a sudden change in condition of motion of the device to close said valve.

15 9. In a constant level liquid supply device, a reservoir having an inlet connection, an inlet valve in said connection, a valve actuating mechanism including a float in said reservoir operable to maintain a substantially constant depth of fuel in the reservoir, and another valve actuating mechanism operable responsive to sudden change in condition of motion of the device to close said inlet valve independently of said first-mentioned mechanism, said other valve actuating mechanism including a movable member mounted within said reservoir to close said valve responsive to impact of a body of fuel moving generally transverse to the depth direction of the fuel in the reservoir responsive to a sudden change in condition of motion of the device.
